Primary Examiner—Janice E. Seeger**[57] CLAIM**

The ornamental design for an neck and shoulder pillow, as shown and described.

DESCRIPTION

FIG. 1 is a perspective view of a neck and shoulder pillow, showing my new design; the broken lines are for environmental purposes only and form no part of the claimed design;

FIG. 2 is a rear perspective view;

FIG. 3 is a rear view of the present invention;

FIG. 4 is a left side view of the present invention, the right side view being a mirror image thereof;

FIG. 5 is a front view of the present invention;

FIG. 6 is a top view of the present invention;

FIG. 7 is a bottom view of the present invention; and,

FIG. 8 is a cross section view taken along line 8—8 of FIG. 3.
